DESIGN FOR A ONE CUP DRIP COFFEE MAKER

Joseph Block, New York, N. Y., assignor to J. & I. Block, New York, N. Y., copartnership composed of Irving Block, Dorothy Block, and said Joseph Block

Application April 30, 1943, Serial No. 110,083

Term of patent 7 years

To all whom it may concern:

Be it known that I, Joseph Block, a citizen of the United States of America and a resident of New York, in the county of New York and State of New York, have invented a new, original, and ornamental Design for a One Cup Drip Coffee Maker, of which the following is a specification, reference being had to the accompanying drawing, forming a part thereof.

In the drawing:

The characteristic features of my design reside in the portions shown in full lines.

This application is a continuation-in-part of my applications, Serial Nos. D-109,719 and D-109,720, filed March 10, 1943.

I claim:

The ornamental design for a one cup drip coffee maker, as shown and described.

JOSEPH BLOCK.
